Primary Examiner — Holly E Thurman*Assistant Examiner* — Altaira J Swangin(74) *Attorney, Agent, or Firm* — Aronberg Goldgehn Davis & Garmisa(57) **CLAIM**

The ornamental design for a dispenser base, as shown and described.

DESCRIPTION

FIG. 1 is a perspective view of a dispenser base, showing our new design;

FIG. 2 is another perspective view, shown in use with environment;

FIG. 3 is a side view thereof;

FIG. 4 is the opposite side view thereof;

FIG. 5 is a top plan view thereof;

FIG. 6 is a bottom plan view thereof;

FIG. 7 is a front view thereof; and,

FIG. 8 is a rear view thereof.

The broken lines, showing dispensers mounted on the dispenser base in FIG. 2, represent environment that forms no part of the claimed design. All other broken lines show portions of the dispenser base and form no part thereof.
